(57) **CLAIM**

The ornamental design for a beverage machine, as shown.

DESCRIPTION

FIG. 1 is a front perspective view of a beverage machine in accordance with the invention;

FIG. 2 is a rear perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof;

FIG. 8 is a bottom view thereof; and,

FIG. 9 is a front perspective view thereof in a loading position.

Portions of the design shown in dashed lines form no part of the claimed invention but instead are shown for context or environment only.
